HINGE WITH NON-RISING PIN

John S. Parsons, West Hartford, Conn., assignor to The Stanley Works, New Britain, Conn., a corporation of Connecticut

Filed Aug. 31, 1961, Ser. No. 135,178

1 Claim. (Cl. 16—169)

The present invention relates to hinges comprised of a pair of leaves having interfitting knuckles with a pin extending therethrough to provide a pivotal connection therebetween and, more particularly, to such a hinge wherein the hinge pin is retained against undesired movement during normal operation.

It is an object of the present invention to provide a hinge assembly incorporating novel and durable means for retaining the hinge pin against undesired movement thereof and capable of accommodating variations in diameter of the hinge pin.

Another object is to provide a hinge assembly incorporating relatively inexpensive and highly effective pin retaining means which is readily assembled and in which the pin may be readily disengaged when so desired.

It is also an object to provide a novel hinge assembly having such pin retaining means in combination with a relatively narrow diameter barrel portion and hinge pin and wherein the pin is retained against unintentional movement both axially and rotationally.

Other objects will be in part obvious and in part pointed out more in detail hereinafter.

The invention accordingly consists in the features of construction, combination of elements and arrangement of parts which will be exemplified in the construction hereafter set forth and the scope of the application which will be indicated in the appended claim.

In the drawings:

FIG. 1 is a fragmentary front elevational view of an opened hinge embodying the invention and having the barrel in section to reveal internal construction;

FIG. 2 is a side elevational view of the pin retaining sleeve;

FIG. 3 is a bottom view of the sleeve; and

FIG. 4 is a fragmentary sectional view of the lower barrel showing the hinge pin about to be seated in the sleeve,

Referring now in detail to the drawings, a hinge embodying the invention is illustrated as comprised of the fragmentarily illustrated sheet metal leaves 2, 4 having integrally formed interfitting rolled knuckles 6, 8, 10 which are of substantial axial length. Extending through the several knuckles 6, 8, 10 are coaxial and aligned bores 12, 14, 16 in which is disposed the elongate shank 18 of the hinge pin 20 which provides a pivotal connection between the leaves, and the shank 18 is provided with a chamfered end portion 19 for guiding the pin through the hinge elements. In assembly, the head 22 of the hinge pin 20 is fitted tightly against the outer end of the knuckle 6.

The relatively narrow diameter shank 18 of the hinge pin 20 is radially spaced and non-rotatably supported within the bores 12, 14 of the knuckles 6, 10 of the leaf 4 by the tubular sleeves 24, 26. The outer diameter of the sleeves 24, 26 is dimensioned to form a tight fit with the inner surface of the knuckles 6, 10 so as to require force-fitting and the inner diameter is dimensioned to provide a sliding fit with the shank 18 which will result in some measure of frictional engagement therebe-

2

tween. The sleeves 24, 26 have radial flanges 28, 30 at one end which seat in shallow counterbores at the inner ends of the knuckles 6, 10 and the metal of the knuckles is then staked so as to deform some of the metal over the flanges 28, 30 and lock the sleeves 24, 26 firmly therein.

The lower sleeve 26 has a lower end portion 32 of reduced outer diameter providing a spacing between it and the inner surface of the knuckle 10. A pair of diametrically spaced, axial slots 34 in the end portion 32 define a pair of spring fingers 36 therebetween. As best seen in FIGS. 2-4, the end portion 32 is crimped without changing the radius of curvature so that the fingers 36 normally incline inwardly to a distance between their free ends smaller than the outer diameter of the pin shank 18. The free ends of the spring fingers 36 are bent inwardly to the position shown in FIG. 3, as for example by placing the sleeve 26 in a punch press and applying pressure at the midpoints of the fingers 36 along a line perpendicular to a line through slots 34 so that the free ends of the arcuate spring fingers 36 bear upon the surface of the shank 18 at about their midpoints so that the pin is firmly engaged thereby and prevented from rising inadvertently and also from rotating therein. With this engagement between the midpoints of the free ends of the fingers 36 and the pin shank 18, the holding power of the spring fingers of the pin is stabilized at the desired level by the insertion and withdrawal of the pin during the manufacture of the hinge with the result that repeated insertions and withdrawals of the pin during use do not cause a significant variation in the holding power of the fingers.

Although more than two axial slots may be utilized to provide a greater number of spring fingers, the illustrated embodiment with two slots providing a bifurcated end portion has proven most satisfactory in that a suitable degree of resiliency is provided commensurate with a high degree of holding power. Utilization of a greater number of slots will increase the resiliency but will materially reduce the holding power and also decrease the ease of fabrication.

It will be noted that the ends of the spring fingers 36 bear upon a shank surface of uniform diameter so that the holding power is thus provided by the resilient connection permitting ready disengagement of the hinge pin when so desired. Although the surface of the pin shank 18 may be roughened to effect some increase in holding power, the use of pins with relatively smooth surface produced in accordance with conventional fabrication and finishing techniques has proven highly satisfactory.

Force-fitted into the bottom end of the lower knuckle 10 is a hinge tip 38 having an aperture 40 extending axially therethrough to permit insertion of a nail or tool for unseating the hinge pin from the spring fingers and driving the hinge pin outwardly of the barrel to effect disengagement.

In accordance with the preferred aspect of the invention, the illustrated hinge employs the novel pin support and bearing assembly which forms the subject of my co-pending application Serial No. 94,872, filed March 10, 1961. In this embodiment, the elongate and relatively narrow diameter pin shank 18 is seated in ball-bearing assemblies 42 which function as combined thrust and radial bearings for the hinge and have portions extending radially inwardly of the knuckle bores.

Each of the ball bearing assemblies is comprised of a movable raceway 44 and a stationary raceway 46 having a portion 48 extending axially within the bore 14 of the

knuckle 8 and which is press-fitted or otherwise fixed therein. The raceways 44, 46 move relative to each other upon the balls 50, and the bore through the stationary raceway 46 is of larger diameter than that of the movable raceway 44 so that a spacing exists between the axially extending portion of the inner bearing case 52 which, in cooperation with the outer bearing case 54, maintains the bearing assembly as a unit and provides a dirt seal therefor while simultaneously retaining grease or lubricant between the raceways. The pin shank 18 and bearing assemblies 42 are so dimensioned that the pin forms a sliding fit with the inner case 52 and thereby with the movable raceway 44, and the stationary raceway 46 is movable relative to the pin and the remainder of the bearing assembly without binding.

As shown, there is a substantial axial spacing between the axially extending portions 48 of the ball-bearing assemblies, and in this axial spacing is fitted an annular sleeve 56 through which the pin shank 18 freely extends. Although two or more annular sleeves may be employed in this axial spacing depending upon the length, it has been found that a single sleeve intermediate the bearing assemblies provides a highly effective assembly. The internal aperture of the annular sleeve 56 is of slightly larger diameter than the shank 18 of the hinge pin so as not to bear upon the pin during relative rotation of the leaves during normal operation of the hinge but to provide radial support for the pin intermediate the ball-bearing assemblies 42 and prevent excessive flexure of the pin under shock or stress loads such as would permanently deform it. The sleeve 56 is preferably fabricated from a material having a relatively low coefficient of friction such as nylon, "Delrin" or linear polyethylene in order to provide a satisfactory non-wearing surface when called into play.

Although the bore 16 of the lower knuckle 10 may be enlarged with respect to the bores 12, 14 in the other knuckles 6, 8 to accommodate the radial thickness thereof for utilization in other types of leaf hinge assemblies, the present invention has been found particularly advantageous in sheet metal hinges with rolled knuckles providing bores of uniform diameter and, accordingly, the illustrated bearing and pin support assembly which permits highly effective and long-lasting utilization of a narrow diameter pin.

It has been found that the pin holding means of the present invention is both relatively economical and rugged and will satisfactorily engage pins varying to a substantial degree from the intended diameter which are occasionally inadvertently substituted during assembly either at installation or at other times. To ensure proper operation, the spring fingers 36 are crimped so that they taper to a width at their free ends substantially less than the intended pin diameter, generally ranging from about ten percent less for a relatively thin pin to about five percent less for a relatively thick pin. The spring fingers 36 of the sleeve are not heat-treated subsequent to the crimping operation in order to avoid creating an excessive spring action in the spring fingers and thus accommodate major expansion and resizing as the result of the use of a pin of larger than intended diameter. As the pin seats in the end portion 32, the spacing between the spring fingers 36 becomes resized to some extent, and the cold-working of the metal occurring during the expansion tends to increase the resiliency of the spring fingers and thereby the holding power. Consequently, although the initial insertion of the pin will resize the spring fingers to some extent, a substantial portion of the holding power will be retained during the repeated insertions and withdrawals of the pin due to the natural springback of the metal.

The crimping of the spring fingers without altering the radius of curvature ensures that the free ends of the spring fingers 36 will bear upon the pin at their midpoints rather than at the side regions adjacent the slots, thereby materially reducing the strain on the fingers dur-

ing insertion of the pin and, accordingly, reducing permanent deformation of the spring fingers effected thereby.

In assembling the hinge, the pin shank 18 is inserted into the bore 12 of the upper knuckle 6 and guided by the sleeve 24 through the upper bearing assembly 42. The pin shank 18 then passes through the annular sleeve 56 which cooperates with the upper sleeve 24 to guide the pin shank through the lower bearing assembly 42 and thence into the lower sleeve 26. As the pin shank 18 moves down into the lower end portion 32, it spreads the inwardly inclined spring fingers 36 until it passes therethrough, and the pin 20 finally seats in the barrel with its head 20 firmly against the outer end of the upper knuckle 6.

In operation of the hinge, the pin is frictionally engaged in the sleeves 24, 26 and secured by the spring fingers 36 so that there is no tendency for the pin to turn relative to the knuckles 6, 10 of the leaf 4 or the movable raceway 44 and inner bearing case 52 so that there is no frictional wear with these elements. The stationary raceway 46, which is press-fitted into the knuckle 8, moves with the leaf 2 and its effective contact with the jamb leaf 4 is solely through the balls 50. Thus, in this assembly no frictional wear occurs during normal operation of the hinge and, although the narrow diameter pin is relatively flexible, the effect of the bending forces upon the pin by reason of its pivotal connection at the bearing assemblies, is minimized by the annular sleeve 56 which provides radial support therefor between the bearing assemblies and prevents excessive deformation of the pin during shock or stress loading of the hinge.

Disassembly of the hinge leaves can be readily effected merely by inserting a nail or other tool into the aperture of the hinge tip and applying sufficient force to dislodge the pin from the spring fingers and then drawing the pin outwardly of the hinge barrel. The pin will be guided by the several sleeves through the ball-bearing assemblies so as to avoid damage thereto.

By the present invention, a relatively economical and easily assembled and disassembled hinge is provided which retains the hinge pin against inadvertent axial and rotative movement. The pin retaining means will accommodate a fairly substantial variation in hinge pin diameter while providing a high degree of holding power which it will continue to exert even after repeated disassembling. This hinge pin retainer is particularly advantageous in combination with the pin support and bearing assembly illustrated in the drawings wherein it ensures substantial immobility of the pin during normal operation so as to eliminate frictional wear of the elements for a highly effective and long-lasting hinge assembly.

As will be apparent to persons skilled in the art, various modifications and adaptations of the structure above described will become readily apparent without departure from the spirit and scope of the invention, the scope of which is defined in the appended claim.

I claim:

In a hinge having a pair of leaves provided with interfitting knuckles having coaxial bores extending therethrough, the combination therewith of a nonrising pin assembly comprising a sleeve positioned in the lowermost knuckle and secured therein against longitudinal and rotative movement relative thereto, said sleeve having a lower end portion spaced inwardly from the inner surface of the lowermost knuckle to provide an annular clearance therewith, said end portion having a pair of axially extending slots therein defining resilient fingers therebetween, said fingers being normally inclined radially inwardly to provide an internal aperture between the free ends thereof, a removable hinge pin extending through said knuckles and beyond the lower end of said sleeve and being of a diameter greater than the distance between the free ends of said fingers, the free ends of the fingers having a greater radius of curvature than the end of said hinge

pin so as to engage the same along substantially opposed lines of contact to secure the pin against axial and rotative movement relative to the lowermost knuckle of the hinge.
